UNITED STATES PATENT OFFICE.

ARTHUR LEE HOLCOMB, OF NEW CANAAN, CONNECTICUT.

HOUSEHOLD APPARATUS FOR KITCHEN AND CULINARY USES.

Application filed October 15, 1919. Serial No. 330,723.

To all whom it may concern:

Be it known that I, ARTHUR L. HOLCOMB, a citizen of the United States, and resident of New Canaan, in the county of Fairfield and State of Connecticut, have invented certain new and useful Improvements in Household Apparatus for Kitchen and Culinary Uses, of which the following is a specification.

10 This invention relates to household apparatus for kitchen and culinary uses, and it has special relation to apparatus of this class which is interchangeably adapted for use in divers purposes. The object of my 15 invention is to provide a simple and improved household apparatus of the character set forth which will possess advantages in point of convenience, effective operation and general efficiency, in the various interchangeable offices for which it is employed.

In the drawings—

Figure 1 is a side view, partly in section, illustrating the main body of the improved apparatus.

25 Fig. 2 is a top or plan view of the construction as illustrated in Fig. 1, with the cover removed.

Fig. 3 is a side view, partly in section, of the operative attachment for the use of the 30 apparatus as a dish washer.

Fig. 4 is a top or plan view of the construction shown in Fig. 3 and illustrating the same in position within the body reservoir of the apparatus.

35 Fig. 5 is a side view, partly in section, of the operative attachment for the use of the apparatus as a vegetable peeler.

Fig. 6 is a top or plan view of the construction shown in Fig. 5 and illustrating 40 the same in position within the body reservoir of the apparatus.

Fig. 7 is a side view partly in section, of the operative attachment for the use of the apparatus as a clothes washer.

45 Fig. 8 is a top or plan view of the construction shown in Fig. 7 and illustrating the same in position within the body reservoir of the apparatus.

Fig. 9 is a side view, partly in section, of 50 the operative attachment for the use of the apparatus as an ice cream freezer or churn or other analogous purposes, the same being shown in operative position within the body reservoir of the apparatus.

Fig. 10 is a top or plan view, partly in section, of the construction as shown in Fig. 9.

Corresponding parts in all of the figures are denoted by the same reference characters.

Referring to the drawings, 1 designates the reservoir body of the apparatus, which is suitably mounted upon standards or legs, 2, and constitutes a receptacle having a horizontal bottom, 3, and side walls, 4. The body receptacle 1 is closed by a top or cover, 5, preferably consisting of two half-sections, 6—6, hinged together at the median line of the top, as at 7, said sectional top having one section hinged, as at 8, to the top edge of the side walls 4 and being in its contour 5, preferably of substantially dome shape or convexo-concave in cross-section, to afford a dome chamber, as at 9, above the operative attachment which is contained within the reservoir, and having its first section provided with a suitable handle, 10, whereby the top or cover may be conveniently opened up. From the bottom of the body receptacle depends and extends a suitably arranged pipe, 11, having a valve-control, 12, 65 for drawing off the waste water, and into the side wall 4, at a suitable point above the bottom of the receptacle or adjacent the top thereof, extend suitably arranged pipes, as at 14—15, respectively having a valve control, as at 16—17, and respectively serving as a cold and hot water supply to the body reservoir. Within the reservoir 1, suitably mounted in connection with the side walls 4 and adjacent the top thereof, is provided a sprinkler constituted by a perforated pipe, 18, extending circumferentially of the reservoir and conforming to the contour of the walls thereof and having a branch pipe, as at 19, extending to the water supply pipe 14 and provided with a valve control, as at 20, said sprinkler being fed from the pipe 14 and being operative to spray or sprinkle convergently towards the center of the reservoir or receptacle and over the contents 95 thereof. A corresponding branch pipe may also be provided from the sprinkler pipe to the other water supply pipe 15, if desired.

A vertical shaft, 21, is mounted at the base of the reservoir body and has a stud 105 end, 22, projecting within the reservoir through the bottom 3 and centrally thereof, said shaft being supported by a flange bear-

ing, 23, provided in a bearing block, 24, beneath the bottom 3, and carrying at its lower end a bevel gear, 25, whereby a rotary motion is transmitted to said shaft. Said bevel gear is preferably operative in an oil chamber, 26, and the shaft is provided with a flange gasket, 27, operative above the bottom 3 to prevent the passage of water in the reservoir to the oil chamber. The shaft 10 21 may be driven by any suitable power, but I prefer to employ in the composite domestic apparatus for which my invention is especially designed an electric drive consisting of a motor, indicated at 28, connected with 15 a circuit or source of electrical energy and having its shaft, 29, carrying a bevel pinion, 30, projecting within the oil chamber 26 and meshing with the gear 25, said motor mechanism being of any adapted type having a 20 control lever, as at 31, and a resistance, as at 32, and whole being enclosed within a suitable casing, 33, mounted beneath the reservoir body 1 and from which the control lever 31 is projective.

25 The horizontal cross-sectional contour of the reservoir body or receptacle is such that the side walls 4 thereof form a successive series of segments, as at 34, the termini of said segments being at the circumference 30 of a true circle which forms the central body space or area (indicated by the dotted line 35 in Fig. 2) of the reservoir and beyond which said segments form a series of successive circumferential body chambers or 35 areas, as at 36, the walls of which are respectively of convexo-concave contour. Any suitable plurality of the segments 34 may be provided, but I prefer to form the enclosing side walls 4 of the body reservoir with four 40 of such segments, the arc of each of which is part of a true circle (indicated by the dotted lines 37 in Fig. 2) the circumference of which intersects the center or axis of the reservoir space at the shaft stud 22, which 45 axis is the center of the true circle forming the central space or area 35 of the reservoir. The interior contour of the body reservoir, as just described, thus affords five circular areas, the main area being the true circular 50 space 35 at the central part of the reservoir within the termini of the outer segments 34, and the other four areas being the successive true circular spaces 36 of which the segments 34 respectively constitute a part 55 of the circumference and which intersect each other and also intersect the central circular area 35; and, in operation, when a rotary motion is imparted to the water within the reservoir, the movement of the water 60 is not in a circular path, as would be the case if the reservoir was of a true cylindrical contour in horizontal cross-section, but is deflected by each of the segments 34 in the direction indicated by the arrows in Fig. 2, 65 which deflection within each segment directs

the water in the line of the circular path thereof towards the center of the reservoir and breaks up the circular path of travel and thus effects a maximum degree of agitation of the water in multiple segmental 70 paths which intersect and co-act in different lines of deflection.

The foregoing operative action is an important factor in the efficiency and effectiveness of the apparatus in the interchangeable purposes for which it is adapted. Such interchangeable purposes are accomplished by various attachment devices which are adapted for mounting within the reservoir or receptacle and in connection with the 75 rotary shaft 21 and which are attachable and removable therefrom. A large variety of interchangeable attachment devices may be thus employed, and I have herein illustrated several types thereof which are 80 adapted to form parts of a combination apparatus in the various uses for which the main body apparatus can be employed.

In Figs. 3 and 4, I have illustrated an attachment device adapted for use as a dish 85 washer and consisting of a cylindrical skeleton cage, 38, formed of wire netting and having side walls, 39, the interior space of which is divided into various compartments, 40, by vertical partitions, 41, adapted to 90 contain various articles of table ware, and a bottom, 42, having a central or axial socket, as at 43, adapted to fit over and interlock with the stud end 22 of the shaft 21. Said dish washing attachment has its cylindrical 95 diameter conforming to the true circle 35 of the central body space or area of the reservoir 1, and is adapted to revolve therein, in which action the deflected movement of the water within the reservoir, as before described, will operate to effectively and rapidly cleanse the articles carried by the wire netting attachment 38, as will be readily understood.

In Figs. 5 and 6, I have illustrated an attachment device adapted for use as a vegetable peeler, and in this instance of use the deflected action of water within the reservoir is not an element of the operation. Accordingly, said attachment device consists of 110 a hopper, 44, adapted to fit within the interior space of the body reservoir 1 and conforming thereto and having its side walls, 45, converging or curved inwardly at their base, as at 46, to close the bottom portion of 115 the outer segmental spaces or areas 36 formed by the segments 34 and prevent the vegetables from dropping to the bottom of the reservoir. Said side walls 45 converge to a bottom opening, 47, in the hopper 44, 120 which opening is circular and conforms to the central circular body space or area 35 of the reservoir, 1, and within said bottom opening operates a turn-table, 48, conforming thereto and having a central or axial 125

socket, 49, adapted to receive and interlock with the stud end 22 of the shaft 21, whereby a rotary motion is imparted to said bottom closure turn-table. The peeling attachment device 44 is operative upon potatoes and other vegetables and upon various fruits and is preferably constructed with its hopper and turn-table formed of sheet metal having the interior surface thereof lined 5 with a suitable abrasive, as at 50, such as a coarse emery cloth, and the hopper being stationary the rotary action of the turn-table will carry the contained vegetables in contact with the abrasive walls of the device and 10 thus effectively and quickly peel the contents. In the peeling operation, the same deflected paths of travel of the contents of the hopper are caused as those above described with reference to the conditions when water 15 is used in the reservoir 1, as the hopper 44 conforms to the same segmental and circular conditions of horizontal cross-sectional contour as exist in the side walls 4 of the reservoir 1 and thus the effective operation 20 and action upon the vegetables is correspondingly enhanced.

In Figs. 7 and 8, I have illustrated an attachment device adapted for use as a clothes washer. This device consists of a circular 25 turn-table, 51, having a central or axial socket, 52, adapted to receive and interlock with the stud end 22 of the shaft 21, and carries at its top a circumferential series of upwardly-projecting fingers, 53, which are 30 inclined outwardly and form a shallow basket which is operative to retain the clothes upon the turn-table and effect the carriage of the same thereby during the rotary movement of the turn-table within the 35 reservoir 1. The diameter of the turn-table, 51, inclusive of its projective fingers, conforms to the width of the central circular body space or area 35 of the reservoir 1 which is within the terminii of the outer 40 segments 34 of the walls of said reservoir or receptacle. In the operation of this attachment device, the clothes are carried in a rotary movement within the water in the reservoir 1 and the deflected action of the water 45 in the multiple segmental paths, caused by the outer segments 34 which form the circumferential body chambers or areas 36, produces an enhanced effective operation in the 50 rapid cleansing of the clothes, the horizontal 55 cross-sectional contour of the reservoir or receptacle, as hereinbefore described, being particularly adapted for an efficient operative effect in the use of the apparatus with the clothes washing attachment device.

50 In Figs. 9 and 10, I have illustrated an attachment device of a character which is adapted for use as an ice cream freezer or a churn or for other analogous purposes. This device comprises a cylindrical container, 54, having side walls and a bottom 55

and an open top and adapted to contain the cream or other fluid to be acted upon, the bottom having a central or axial socket, 55, adapted to receive and interlock with the stud end 22 of the shaft 21, whereby said container may be revolved. The top of the container is operatively closed by a cover, 56, from which projects downwardly within the container a rod, 57, carrying laterally-projecting fingers, 58, which are operative to agitate the contents of the container as the latter is revolved. Said cover or top-piece 56 is adapted to interlock with the top or cover 5 of the body reservoir or receptacle 1, to maintain a stationary position of the rod 57 and fingers 58 with relation to the revolution of the container 54, and for this purpose said top-piece 56 of the container is provided with a transverse rib, 59, projecting from its top surface and received between and interlocking with two parallel ribs, 60—60, provided at the under side of the sections 6 of the hinged reservoir top or cover 5 transversely of the median line at which said sections are hinged together. In 90 the employment of this device as an ice cream freezer, the container 54 may be surrounded by ice placed in a suitable receptacle or otherwise contained within the main body reservoir 1.

I do not herein specifically claim the ice cream freezer or churn attachment means, as above described in relation to the main body and reservoir or receptacle and operative mechanism of the parent apparatus as herein set forth, as these specific devices are shown in example or illustration of various other attachments which may be interchangeably employed for operative service 100 in connection with the parent apparatus, but the right is reserved to claim the features of said ice cream freezer or churn attachment devices, in their relative construction and arrangement, under a separate application for patent.

It will be understood that various other attachment devices may be employed, other than those herein shown and described, adapted for interchangeable operative service for divers purposes in connection with the main body and reservoir or receptacle 115 and operative mechanism of the parent apparatus as herein set forth, and I do not restrict myself to any specific set of attachment devices, as the main or parent apparatus may be commercially produced and employed with various combinations of subsidiary and interchangeable attachment devices for various purposes as desired.

Having thus described my invention, I 125 claim and desire to secure by Letters Patent:

1. A household apparatus of the class described, comprising a main body receptacle having a bottom and side walls, the horizontal cross-sectional contour of the receptacle 130

body being such that the side walls form a continuous and successive series of segments the terminii of which are at the circumference of a true circle forming the central body space or area of the receptacle and beyond which central area said segments form a continuous series of successive body chambers or areas collectively constituting the complete circumferential wall of the body receptacle and the walls of which are respectively of convexo-concave contour, whereby the body space is surrounded by a continuous series of connecting and successive concave chambers, a stud shaft axially projective within the bottom of said receptacle, means for imparting a rotary motion to said shaft, inlet and outlet pipes for controlling a water supply to said receptacle, and an attachment device attachable to and detachable from said stud shaft and operative in a rotary movement in said central body space or area of the receptacle as a carrier for the articles being subjected to the action of the apparatus, substantially as and for the purpose set forth.

2. In a household apparatus of the class described, a receptacle having a horizontal cross-sectional contour in which the side walls form a continuous and successive series of segments the terminii of which are at the circumference of a true circle forming the central body space or area and beyond which central area said segments form a continuous series of successive body chambers or areas collectively constituting the complete circumferential wall of the body of the receptacle and the walls of which are respectively of convexo-concave contour, whereby the body space is surrounded by a continuous series of connecting and successive concave chambers, and rotary means for carrying the articles to be acted upon within the receptacle, substantially as and for the purpose set forth.

3. A household apparatus of the class described, comprising a main body receptacle having a bottom and side walls, the horizontal cross-sectional contour of the receptacle body being such that the side walls form a continuous and successive series of segments the terminii of which are at the circumference of a true circle forming the central body space or area of the receptacle and beyond which central area said segments form a continuous series of successive body chambers or areas collectively constituting the complete circumferential wall of the body receptacle and the walls of which are respec-

tively of convexo-concave contour, whereby the body space is surrounded by a continuous series of connecting and successive concave chambers, a stud shaft axially projective within the bottom of said receptacle, means for imparting a rotary motion to said shaft, inlet and outlet pipes for controlling a water supply to said receptacle, and an attachment device attachable to and detachable from said stud shaft and operative in a rotary movement in said central body space or area of the receptacle as a carrier for the articles being subjected to the action of the apparatus, substantially as and for the purpose set forth.

4. In a household apparatus of the class described a receptacle having a horizontal cross-sectional contour in which the side walls form a continuous and successive series of four segments the arc of each of which is part of a true circle the circumference of which intersects the center or axis of the receptacle, the terminii of said segments being at the circumference of a true circle which forms the central body space or area of the receptacle and beyond which said segments form a continuous series of four successive body chambers or areas collectively constituting the complete circumferential wall of the body of the receptacle and the walls of which are respectively of convexo-concave contour, whereby the body space is surrounded by a continuous series of four connecting and successive concave chambers, and rotary means for carrying the articles to be acted upon within said receptacle, substantially as and for the purpose set forth.

5. In a household apparatus of the class described, a receptacle having a horizontal cross-sectional contour which forms a circular central body space or area and having beyond said central space or area a continuous series of successive segmental outer body chambers or areas opening to said circular central space and collectively constituting the complete circumferential wall of the body of the receptacle, whereby the body space is surrounded by a continuous series of connecting and successive segmental chambers, and rotary means operative within said circular central body space or area for carrying the articles being subjected to the action of the apparatus, substantially as and for the purpose set forth.

In testimony whereof I have signed the foregoing specifications.

ARTHUR LEE HOLCOMB.
